UNITED STATES PATENT OFFICE.

HARRY F. GEIST, OF RACINE, WISCONSIN, ASSIGNOR, BY MESNE ASSIGNMENTS, TO WEBSTER ELECTRIC COMPANY, OF RACINE, WISCONSIN, A CORPORATION OF WISCONSIN.

MAGNETO-MACHINE.

1,267,755.

Specification of Letters Patent.

Patented May 28, 1918.

Application filed April 12, 1916. Serial No. 90,631.

To all whom it may concern:

Be it known that I, HARRY F. GEIST, a citizen of the United States, residing at Racine, in the county of Racine and State of Wisconsin, have invented a certain new and useful Improvement in Magneto-Machines, of which the following is a full, clear, concise, and exact description, reference being had to the accompanying drawings, forming 10 a part of this specification.

My invention relates to magnetos for ignition purposes, and more specifically stated, my present invention is directed toward the provision of an efficient high tension magneto of the unwound oscillating rotor type. The embodiment of my invention herein after described in detail is characterized not only by its electric and magnetic efficiency, but also by the simplicity of its construction 15 and the ease with which its several component parts may be assembled in the course of manufacture.

Inasmuch as my invention will more readily be understood from a description read in 20 connection with the accompanying drawings, I shall without further introduction proceed to the detailed description of my improved magneto machine.

In the accompanying drawings—
30 Figure 1 is a front elevational view of my improved ignition magneto.

Fig. 2 is a somewhat similar view illustrating the magneto with certain parts removed to reveal the windings and inter- 35 rupter devices.

Fig. 3 is a view partly in section and partly in elevation, taken in a vertical plane on the line 3—3 of Fig. 1, and looking in the direction indicated by the arrows.

Fig. 4 is a view partly in horizontal section and partly in top plan, taken on the line 4—4 of Fig. 3, and looking in the direction indicated by the arrows.

Fig. 5 is a view partly in elevation and 45 partly in vertical section, the section being taken on the line 5—5 of Fig. 3 and looking in the direction indicated by the arrows.

Fig. 6 is a more or less diagrammatic view somewhat similar to Fig. 5, but illustrating 50 the rotor in the position to which it is moved and released by the engine driven actuator.

Fig. 7 is an isolated view in perspective of one of the coil carrying pole pieces with which the machine is provided.

Fig. 8 is a diagram of the primary and 55 secondary circuit connections, and

Fig. 9 is a diagram of a modified circuit arrangement.

Similar characters of reference refer to similar parts throughout the several views. 60

Referring first to Figs. 1 to 4 inclusive, it will be noted that the machine framework comprises the permanent front and rear plates indicated at 10 and 11 respectively. Clamped between the ends of the plates 10 65 and 11 by rivets passing therethrough are the pole pieces of the machine, each of which is indicated as a whole by the reference numeral 12. As most clearly shown in Figs. 5 and 7, each of the pole pieces 70 comprises a plurality of substantially E shaped soft iron laminæ 12^b, each of which has its outer edge provided with steps to receive the poles of permanent horse shoe magnets 13—13, the magnets being securely 75 clamped in position upon the pole piece laminæ by clamping plates 14—14, each of said clamping plates being secured to the adjacent ends of the permanent front and rear plates 10 and 11 by screws or otherwise, 80 and provided with a central boss through which is threaded a set screw 15, whereby the horse shoe magnets 13—13 are securely clamped in position.

Each of the pole pieces 12 comprises in 85 addition to the substantially E shaped laminæ 12^b a plurality of supplemental soft iron laminæ 12^c, which cooperate with the middle projections of the E shaped laminæ to provide a laminated metal polar projection of considerable width, upon which is carried a primary or generating winding 16. It will be noted that the laminæ 12^c are at 90 their outer edges provided with stepped extensions symmetrical with the corresponding stepped extensions of the E shaped laminæ 12^b and with the latter providing laminated soft iron shelves upon which the magnet poles rest and are secured. Disposed around each of the primary windings is a secondary 100 winding indicated at 17. It will be noticed that although each of the pole pieces comprises three polar projections, in each case the middle projection only carries windings. Attention is directed to the fact that the unwound polar projections of each pole piece 105 are of small breadth as compared to the middle or wound projections. However,

each of the unwound polar projections is, at its extremity provided with blocks 12^a of cold rolled steel, each pair of the steel blocks 12^a together with the laminae 12^b constituting an unwound polar projection of substantially T shape. As is most clearly shown in Figs. 5 and 6, the inner faces of the permanent front and rear plates are provided with channels or depressions 18-18, into which the blocks 12^a extend. The blocks 12^a are thus held against displacement. Moreover, rivets 19-19 extending through registering openings in the front and rear plates, pole piece laminae 12^b and blocks 12^a, serve securely to retain all of these parts together. The extremities of the several pole piece projections are provided with curved faces arranged to coöperate with the projections or prongs of a rotor or inductor presently to be described.

The front and rear plates 10 and 11 have openings therethrough to permit access to the windings and pole pieces, the insertion of the rotor, etc. Secured upon the permanent rear plate 11 is a removable plate 20, which provides a bearing 21 for one end of the rotor shaft 22. Projecting from the inner face of the plate 20 is an annular flange 23, which overlaps the ends of the primary and secondary windings and effectually serves to prevent displacement of the said windings. As is most clearly shown in Figs. 2 to 4 inclusive, the margins of the permanent front plate 10 are cut away to permit the insertion of a block 24 secured in position by screws 24^a extending through the block 24 and engaging in the permanent front plate 10.

The block 24 provides a bearing for the rotor shaft and is moreover provided with an annular flange 25 which in part serves the same purpose as the flange 23 of the removable rear plate 20. However, inasmuch as the outer face of the block 24 lies substantially flush with the outer face of the permanent front plate, by which it is carried, the body of the block 24 in a measure serves as a means for preventing displacement of the primary and secondary windings, the flange 25 serving merely to increase the depth of the block effective for this purpose.

The block 24 not only serves to journal the rotor shaft, but also carries the devices for interrupting the primary circuit at the proper time in the cycle of the operation of the magneto machine. Carried by the block 24 at the upper end thereof but insulated therefrom by suitable insulation 26, is a conductor plate 27, from which extends a lug 28, in which is threaded an adjustable screw 29 carrying a fixed interrupter contact 30 of any suitable material, for instance, of tungsten. The conductor plate 27 is conveniently connected in the insulated side of the primary circuit by means of a screw 31 extend-

ing through insulating bushings 32 and 33 carried by the block 24 and permanent front plate 10 respectively. I shall not at this time go into a description of the circuit connections, but shall defer description of the circuits and the operation of the machine until the structural features of the machine have been more fully explained.

Pivoted upon the block 24 is a small bell crank lever 34, having one arm thereof provided with an interrupter contact 30^a, normally held in engagement with the fixed interrupter contact 30 previously referred to, and as is most clearly illustrated in Fig. 2 of the drawings. A leaf spring 35 having one end thereof secured to a small bracket or lug 36 and its other end secured to the contact carrying arm of lever 34, normally retains interrupter contact 30^a in engagement with its coöperating contact 30. The power arm 85 of the lever 34 lies immediately adjacent to a cam 37 carried by and conveniently keyed upon the rotor shaft 22. I shall presently explain how in the operation of the machine the cam 37 serves to actuate the lever 34 and thus to effect the separation of the interrupter contacts.

Secured by screws to the permanent front plate 10 is a removable plate 38 dished outwardly at its middle portion to accommodate the interrupter devices supported by the block 24 as previously described. The top of plate 38 terminates short of the top of the block 24 and the said plate 38 is provided with a pair of spaced vertical walls 39 with an opening between them, whereby for purposes of adjustment, access may be had to the interrupter devices without disturbing the plate 38. A readily removable sheet metal cap 40 fits around the vertical walls 39-39 and over the top of block 24, as is most clearly shown in Fig. 3, thus effectively preventing dust and dirt from entering the interior of the mechanism.

Although the rotor shaft 22 necessarily extends through the plate 38, the plate is not intended to serve as a bearing, block 24 and removable rear plate 20 being designed to journal the rotor shaft, as has been hereinbefore explained.

Keyed or otherwise fixed upon the forward end of the rotor shaft is a yoke 41 provided at its extremities with anti-friction rollers 42. The clamping plates 14 are provided with forwardly extending arms 14^a 120 provided with anti-friction rollers 42^a. Each arm of the yoke is connected with one of the arms 14^a by a relatively heavy and strong spring 43. The ends of the springs 43 take around the rollers 42 and 42^a, as is most clearly shown in Fig. 4 of the drawings, the said springs 43 normally retaining the rotor shaft and parts carried thereby in the several positions in which said parts are shown in Figs. 1 to 5 inclusive.

Carried by the rear end of the rotor shaft 22 and keyed to the latter is a trip finger 44 arranged to be engaged, oscillated and released by an engine driven actuator indicated by dotted lines at 45 in Fig. 1. The magneto machine is provided with stud bolts 46-46, whereby it may be mounted at any convenient place upon or adjacent to the framework of the engine with which the magneto is associated. I have not thought it necessary to illustrate the engine driven actuator in detail, as the general characteristics of such mechanisms are now quite well known in the art to which my present invention relates. It will suffice to say that at the proper time in the cycle of engine operation the actuating rod 45 engages the magneto trip finger 44 and moves the latter together with the rotor shaft and parts carried thereby against the action of springs 43-43, and then releases the trip finger. At this point I will state that in Patent No. 1,169,612, granted in the name of Walter Brown on January 25, 1916, is illustrated a form of so-called starting lever that is admirably adapted for use in connection with my present magneto machine for the purpose of actuating the mechanism to produce the initial or starting spark.

The rotor or inductor which is most clearly shown in Figs. 3, 4 and 5, is fixed upon the rotor shaft and consists of a plurality of soft iron laminae riveted together to constitute a unitary inductor structure having four radial arms or prongs. The normal position of the inductor is illustrated in Fig. 5. Fig. 6 is a fragmentary diagrammatic view similar to Fig. 5, illustrating the rotor in the position to which it is moved by the engine driven actuator and released.

The laminated rotor or inductor indicated at 47 comprises four arms or prongs as before stated, one pair of said arms or prongs being provided with comparatively broad faced extremities and the other pair with relatively narrow faced extremities. As is most clearly shown in Fig. 6, when the rotor is moved to its actuated or "release" position, the narrow faced inductor arms occupy positions midway between and a substantial distance from their respective adjacent unwound polar projections. When the rotor is in this same position the broad faced inductor arms coöperate with the middle or wound polar projections to direct the magnetic flux through the primary windings. When the trip finger of the rotor shaft is released from the engine driven actuator the springs 43-43 serve quickly to move the inductor to a position such that each of its prongs coöperates with one of the unwound pole piece projections to short circuit the magnetic flux outside of the primary windings. Inasmuch as the faces of

the broad faced inductor prongs are wider than the wound polar projections with which they coöperate the inductor prongs are not located exactly ninety degrees apart, but on the contrary, each of the broad faced prongs is located a trifle closer to one of the narrow faced prongs than it is to the other narrow faced prong, in order that the broad faced prongs may assume the positions shown in Fig. 6 when the narrow faced prongs are in a position midway between their adjacent unwound pole piece projections.

As is most clearly shown in Figs. 3 and 5, a sheet of insulating material 48 lies across the top of the pole pieces in the space spanned by the horse shoe magnets 13-13. This insulating material 48 together with the sheet metal cap 49 secured to the tops of the front and rear plates 10 and 11 by screws, constitutes a housing for a suitable condenser 50, most clearly illustrated in Figs. 3 and 5. As is shown in Fig. 3, an insulating sleeve or stud 51 projects from the permanent rear plate 11, and it is through this insulating sleeve or stud 51 that the insulated conductor of the secondary or high tension circuit extends. The sleeve 51 is conveniently provided with any suitable terminal or clip, for instance, of the type illustrated at 52 in order that the conductor led through sleeve 51 may be connected with the insulated or ungrounded terminal of a spark plug. As is the common practice in ignition systems, both the secondary and primary circuits have one side thereof insulated and the other side grounded, i. e., grounded to the magneto frame or magneto frame and engine frame. Connected with the insulated side of the secondary circuit and projecting from the sleeve 51 is a conductor arm 53, provided at its free extremity with an electrode 54, which is spaced from and disposed directly opposite an electrode 55 carried by and conveniently cast integral with the permanent rear plate 11. It will be understood that the electrodes 54 and 55 constitute a so-called "safety gap", across which a spark may pass if, due to some fault in the outside circuit, the spark cannot pass at the spark plug electrodes.

The circuit arrangement is diagrammatically illustrated in Fig. 8. It will be noted that the primary windings are connected in a series circuit grounded to the magneto framework on one side and having the insulated side thereof led to the stationary interrupter contact 30. The movable interrupter contact is grounded to the machine frame. The condenser 50 is shunted across the primary windings 16-16, one side of the condenser being connected with the insulated side of the primary circuit, the other side of the condenser grounded to the machine frame, as illustrated. The sec-

ondary windings 17—17 are connected in a series circuit having one side thereof grounded and the insulated side thereof led to the insulated electrode of an ordinary spark plug 5 illustrated at 56, the other spark plug electrode being grounded in a well known manner. As has been previously explained, the spaced electrodes 54 and 55 of the emergency gap are positioned between the ground and the 10 insulated side of the secondary circuit to take a spark if for any reason, when a sparking current is induced in the secondary circuit, a spark cannot pass at the spark plug electrodes.

15 The modified circuit arrangement shown in Fig. 9 differs essentially from that of Fig. 8 only in that in addition to the condenser 50 common to both of the primary windings there is provided a pair of supplemental condensers 50^a, connected in shunt of the condenser 50 with the conductor intermediate the condensers 50^a connected with the conductor which connects the primary windings 16—16 in series, whereby 20 each of the condensers 50^a is individual to one of the primary windings in contra distinction to the condenser 50, which is common to both of the primary windings.

Having now in some detail described the 30 construction and electrical connections of my improved high tension magneto machine, I shall explain the operation thereof.

When the engine driven rod or actuator 45 engages and moves the trip finger of the rotor shaft to its actuated or "release" position, the rotor assumes the position shown in Fig. 6, and it will be seen that practically all of the magnetic flux is then directed through the middle projections of the pole 50 pieces 12. After the rotor has been moved to the position shown in Fig. 6 and then released, the springs 43—43 serve quickly to move the rotor back toward and slightly past its normal position, as shown in Fig. 45 5, the slight overthrow of the rotor serving to cause the cam 37 to engage the interrupter lever 34 and thus open the primary circuit at the interrupter contacts. When the rotor is thus by springs 43—43 carried 55 to such a position that the several prongs of the inductor lie opposite unwound polar projections, the magnetic flux, formerly traversing the middle polar projections and primary windings, is short circuited outside of the primary windings. Thus, when the inductor is snapped from "release" position the number of magnetic lines traversing the primary windings drops from a maximum to practically zero, and therefore 60 when the interrupter contacts are opened, with a consequent action of the condenser, a high tension current is induced in the secondary circuit and a spark is caused to pass at the spark plug electrodes. The specific 65 pole piece construction previously described

has much to do with the successful operation of my improved high tension magneto machine. The pole pieces are so constructed that there is sufficient permeable soft iron to permit all of the polar projections to perform their several functions without lagging the current in the secondary circuit. I have found that in a high tension tri-polar machine of the class to which my invention relates, unless substantially the herein described pole piece construction is employed, the iron in proximity to the secondary windings serves to lag the current in the secondary circuit with the result that there is a tendency for a spark to pass at the interrupter contacts of the primary circuit rather than at the jump spark electrodes of the secondary circuit.

Having thus described my invention in more or less detail, what I claim as new and desire to secure by Letters Patent of the United States is:

1. In a magneto machine the combination with a pair of oppositely disposed and symmetrical substantially E-shaped pole pieces, 90 permanent magnets having their poles attached to said pole pieces, generating windings supported by the middle projections of said pole pieces, an inductor movable between said pole pieces and comprising four 95 prongs, alternate prongs having broad faces and the other prongs being narrow faced, each of said narrow faced prongs being closer to one of the broad faced prongs than it is to the other, spring means normally 100 retaining each of said prongs adjacent one of the unwound projections of the pole pieces, and engine driven devices for oscillating the inductor and releasing it at a position such that the broad faced inductor 105 prongs lie opposite the middle pole piece projections for the purpose set forth.

2. A high tension magneto of the class described comprising in combination with a permanent magnet, a pair of oppositely disposed pole pieces each comprising a group of substantially E-shaped soft iron laminæ, two groups of soft iron laminæ disposed one on each side of and supplementing the middle projection of the first group of 110 laminæ and with the latter constituting a single polar projection, a primary winding around said single polar projection, a secondary winding in inductive relation to the primary winding and steel blocks on each 115 side of each of the unwound projections of the first group of laminæ and with the latter constituting pole piece projection extremities of substantially the same width as the middle pole piece projection.

3. A pole piece for a high tension oscillator of the class described comprising a middle polar projection of laminated soft iron adapted to support primary and secondary 120 windings and unwound polar projections on 125

each side of said first mentioned polar projections, said unwound polar projections being substantially T-shaped with the shank of the T of laminated soft iron and the 5 wings of the T of less permeable material.

4. A pole piece of the class described comprising a middle polar projection of comparatively permeable metal adapted to support primary and secondary windings and 10 unwound polar projections on each side of the middle projection, said unwound polar projections being of substantially T-shape with the shank of the T of comparatively permeable material and the wings of the T 15 of less permeable material.

5. A pole piece for a magneto of the class described comprising in combination a middle polar projection adapted to support primary and secondary windings and unwound 20 polar projections on each side of said middle projection said unwound polar projections being of substantially T-shape with the arms thereof extending crosswise of said pole piece.

25 6. A pole piece for a high tension magneto of the class described comprising in combination a middle polar projection adapted to support primary and secondary windings, unwound polar projections on

each side of said middle projection, said unwound polar projections being of substantially T-shape, said pole piece consisting of a group of substantially E-shaped laminæ constituting the central portion of the middle polar projection and the shanks of the 30 T-shaped polar projections, two groups of laminæ supplementing the middle projections of the E-shaped laminæ and blocks having a relatively low coefficient of magnetic permeability disposed on each side of 35 the E-shaped laminæ and constituting the wings of the T-shaped polar projections.

7. In a high tension magneto the combination with a pair of primary windings, secondary windings in inductive relation thereto, a primary circuit including an interrupter, a secondary circuit including a spark gap, a condenser in shunt of both of the primary windings and a pair of supplemental condensers, one in shunt of each of 40 45 the primary windings.

In witness whereof, I hereunto subscribe my name this 8th day of April, A. D. 1916.

HARRY F. GEIST.
